Fig. 1

FIG. 2

FIG. 3

FIG. 1 is a perspective view of a tire showing my new design, it being understood that the tread portion shown is repeated throughout the circumference of the tire and that the shoulder design shown is repeated throughout the circumference of the shoulder, the opposite side of the tire being substantially like the side shown;

FIG. 2 is an enlarged fragmentary plan view of the tread portion of the tire shown in FIG. 1; and

FIG. 3 is a fragmentary transverse sectional view through the tire substantially on the plane indicated by the line 3-3 of FIG. 2.

I claim:

The ornamental design for a tire, substantially as shown and described.
